UNITED STATES PATENT OFFICE.

CHARLES W. GRANT, OF JAMESTOWN, NEW YORK, ASSIGNOR TO GRANT SPECIALTY COMPANY, OF SAME PLACE.

AUTOMATIC OVERFLOW DEVICE FOR REFRIGERATORS, &c.

SPECIFICATION forming part of Letters Patent No. 674,830, dated May 21, 1901.

Application filed August 14, 1900. Serial No. 26,829. (No model.)

To all whom it may concern:

Be it known that I, CHARLES W. GRANT, a citizen of the United States, residing at Jamestown, in the county of Chautauqua and State 5 of New York, have invented new and useful Improvements in Automatic Overflow Devices for Refrigerators, &c., of which the following is a specification.

This invention relates to a device for preventing the overflow of the drip-pans which catch the drippings from refrigerators, wash-stands, and similar devices which are not connected with a drain to carry off the drippings or waste water.

15 The object of my invention is to provide an overflow device for this purpose which is simple and inexpensive in construction and reliable in operation and which will hold the drip-pipe closed while the drip-pan is being 20 removed and emptied, thereby preventing wetting of the parts below the drip-pipe.

In the accompanying drawings, Figure 1 is a vertical longitudinal section of a refrigerator provided with my improved overflow device. 25 Fig. 2 is a fragmentary front elevation of the same, showing the indicator which indicates when the drip-pan has been filled. Fig. 3 is a fragmentary vertical cross-section of the refrigerator and the overflow device in line 30 3 3, Fig. 1. Fig. 4 is a horizontal section in line 4 4, Fig. 1, looking downward. Fig. 5 is a fragmentary vertical section, on an enlarged scale, in line 5 5, Fig. 4, showing the catch whereby the support of the drip-pan is 35 held in position to close the valve in the refrigerator.

Like letters of reference refer to like parts in the several figures.

A represents a refrigerator of any suitable 40 construction and containing the usual compartments for ice and victuals. The refrigerator is supported upon a base or frame a, which forms a drip chamber or space between the bottom of the refrigerator and the floor 45 which receives the drip-pan B and the overflow device.

C represents a drip-pipe which extends 50 downwardly from the bottom of the refrigerator and which is provided with a valve D, having a rotary plug d, whereby the drip- pipe may be opened and closed.

E represents a rocking platform which is arranged in the lower part of the drip-chamber and which is pivoted near its middle, so that it can oscillate in a vertical plane. The 55 pivot of the platform shown in the drawings consists of a pivot-rod e, arranged transversely below the platform and secured at its ends to the side walls of the drip-chamber, and saddles or sockets e', secured to the under side of the platform and engaging over the pivot-rod. The rocking movement of the platform is limited by its ends striking the floor upon which the refrigerator stands or by other means. The platform is connected 60 with the plug of the drip-valve, so that upon rocking the platform in one direction or the other the plug of the valve will be turned, so as to open or close the drip-valve. The preferred means which are employed for 65 transmitting the movement of the platform to the valve-plug and which are shown in the drawings consist of a horizontal shaft, drum, or roller G, connected with the valve-plug, and operating cords or chains g g', connecting said roller with opposite ends of the platform. The roller G is arranged axially in line with the plug of the drip-valve and is connected therewith by engaging the flat- 70 sided handle h of the valve with a transverse 75 slot h' in the inner end of the roller, while the outer end of the roller is journaled in the adjacent side wall of the drip-chamber. The operating-cords g g' are wound with their upper ends in opposite directions around the 80 valve-roller G, and the intermediate parts of the cords pass around guide wheels or rollers i i', arranged on the bottom of the refrigerator. Upon depressing the rear part of the 85 platform the rear cord g' is drawn down and 90 unwound from the valve-roller G, thereby causing the plug of the valve to be turned in the proper direction for opening the same. Upon depressing the front end of the platform the front operating-cord g is drawn 95 down and unwound from the valve-roller, thereby causing the valve-roller G to turn in the opposite direction and closing the drip- valve. When one of the cords unwinds from the valve-roller, the other winds up on the 100 roller, and vice versa, thereby causing the valve to be opened and closed positively.

J represents a movable tray or shelf by which the drip-pan B is movably supported on the platform. This tray rests with its front end upon the front end of the platform, 5 while its rear end is provided with a transverse supporting-roller k, which rests upon the rear end of the platform. The front end of the tray is provided with casters or rollers l, which project downwardly over the front 10 end of the platform and are raised from the floor when the front end of the platform and tray are raised. The tray is capable of sliding in and out upon the platform through an opening l' in the front of the base a and is 15 guided during this movement by two cleats or guide-bars m m, arranged lengthwise on the platform on opposite sides of the tray. The inward movement of the tray on the platform may be limited by a stop of any suitable 20 kind, the stop for this purpose shown in the drawings consisting of the supports l'', by which the casters l are connected with the tray and which are adapted to engage with the front end of the platform. The outward 25 movement of the tray on the platform is limited by a cross-bar N, secured to the rear part of the tray and provided at its ends with stops n n, which are adapted to engage with stops n' n' on the front ends of the guide-bars when 30 the tray is in its foremost position, thereby preventing the tray from becoming disengaged from the platform.

O represents an annular retaining frame, seat, or socket whereby the drip-pan B is held 35 in its proper position on the tray. This socket is secured at intervals to the upper side of the tray by supporting-blocks o', which form spaces between the under side of the socket and the upper side of the tray, 40 through which any water dropping upon the tray within the socket by accidentally spilling the drip-pan may escape therefrom.

P represents a spring-catch which is mounted on the front end of the platform and which 45 is adapted to engage with a shoulder p on the base when the front end of the platform is depressed and hold the same in this position until released by hand.

Preparatory to placing the drip-pan under 50 the drip-pipe the tray is pulled out, and after the drip-pan has been placed in the socket thereof the tray is pushed inwardly until its caster-supports strike the front edge of the platform. In this position of the parts the 55 drip-pan is arranged with its center slightly in front of the drip-pipe and the pivot of the platform. When the drip-pan is empty and in its innermost position on the platform, the weight of the parts is so distributed that the 60 weight on the inner side of the platform-pivot preponderates, which causes the inner ends of the platform, tray, and drip-pan to be depressed until the platform strikes the floor, thereby causing the drip-valve to be opened. 65 The water resulting from the melting ice in the refrigerator now passes through the drip-pipe into the drip-pan and accumulates in

the latter. Owing to the slight rearward inclination of the drip-pan when empty, together with its support, the water first accumulates in the rear or inner part of the pan, thereby adding to the weight which keeps the rear end of the platform and the parts mounted thereon depressed. As the water continues to rise in the drip-pan the greater 70 part of the same accumulates in front of the pivot of the platform. When the water has risen in the drip-pan sufficiently high to cause the weight of the water and other parts in front of the platform-pivot to overbalance 75 the weight of the water and other parts in rear of the platform-pivot, then the front end of the platform is depressed until its casters or front supporting-wheels strike the floor. As the front end of the platform is depressed 80 the plug of the drip-valve is turned so as to close the drip-pipe. After the front end of the platform has been depressed, the tray, with the drip-pan mounted thereon, is pulled forwardly and the pan is removed for emptying 85 the same. The capacity of the pan and its position on the platform while being filled are so determined that the front end of the platform is depressed before the water reaches the top of the pan, thereby permitting the 90 drip-pan to be readily removed without spilling the same. When the front end of the platform has been fully depressed by the overbalancing-weight of the water in the pan, the catch P on the platform passes below the 95 shoulder p on the base and is projected by its spring into engagement with this shoulder, thereby holding the front part of the platform in a depressed position against the lifting tendency of the rear part of the platform, 100 whereby the drip-valve is held closed while the pan is being emptied and the water is prevented from dripping from the drip-pipe upon the platform and flooding the same. After 105 the empty pan has been replaced in its seat on the tray the latter is pushed inwardly to its innermost position, and then the catch P is withdrawn from the shoulder p, thereby permitting the front end of the platform to rise and causing the drip-valve to open, 110 whereby the parts are again in position for conducting the drippings from the refrigerator to the drip-pan. 115

As the tray is moved inwardly and outwardly on the platform the same is supported 120 by means of the rollers at its front and rear ends running on the floor and the platform, respectively.

In order to enable the attendant to determine whether the drip-pan is full or not, the 125 refrigerator is provided with an indicator, which is operated by the movement of the platform and which is constructed as follows:

Q represents the inclosing case of the indicator, which is mounted in the front side of 130 the refrigerator and which is provided with an aperture q.

q' is an indicator-plate which slides vertically in the case in rear of the aperture there-

in and which may be provided on its front side with the word "Full," as shown by dotted lines, Fig. 2.

5 q^2 represents a spring which connects the upper end of the indicator-plate with the casing and holds the same yieldingly in an elevated position.

q^3 represents a cord or chain which connects the lower end of the indicator-plate with the front end of the platform and which extends through a vertical opening q^4 in the refrigerator, extending from the indicator-casing to the drip-chamber. When the front end of the platform is raised, the spring q^2 is permitted to raise the indicator-plate so that the word "Full" is arranged above the aperture in the indicator-case and is not visible. When the front end of the platform is depressed, the indicator-plate is pulled down, so that the word "Full" thereon is exposed through the aperture in the indicator-case. By this means the attendant can determine by an external inspection of the refrigerator when the drip-pan requires to be emptied.

25 Although I have shown my improved overflow device in connection with the drip-pipe of a refrigerator, it is obvious that the same is applicable to other purposes in which similar conditions exist. For instance, the same 30 may be used in connection with the waste-pipe of a wash stand or basin to prevent the waste water from overflowing the waste-water pail or pan.

I claim as my invention—

35 1. The combination with a drip or waste valve provided with a rotary plug, of a drum or shaft connected with said plug, a rocking platform which supports a drip or waste pan below said valve and which is tilted by the 40 weight of the water delivered into the pan, and a connecting means between the rocking platform and said drum or shaft whereby the valve is opened and closed by the rocking movement of the platform, substantially as 45 set forth.

2. The combination with a drip or waste valve provided with a rotary plug, of a drum connected with said plug, a rocking platform which supports a drip or waste pan below 50 said valve and which is tilted by the weight of the water delivered into the pan, and a cord connecting the platform with said drum, substantially as set forth.

3. The combination with a drip or waste 55 valve provided with a rotary plug, of a drum connected with said plug, a rocking platform which supports a drip or waste pan below said valve and which is tilted by the weight of the water delivered into the pan, and two 60 cords which are wound in opposite directions around said drum and which are connected with opposite ends of the platform, substantially as set forth.

4. The combination with a drip or waste 65 valve provided with a rotary plug, of a drum connected with said plug, a rocking platform which supports a drip or waste pan below

said valve and which is tilted by the weight of the water delivered into the pan, and two cords which are wound in opposite directions 70 around said drum and connected with opposite ends of the platform while their intermediate parts pass around guide-rollers, substantially as set forth.

5. The combination with a drip or waste 75 valve, of a vertically-movable platform which is adapted to support a drip or waste pan below said valve so that the drip or waste water from said valve will be delivered into said pan and depress the platform, connecting 80 means which connect said platform with said valve and whereby the valve is closed when the platform is depressed, and a catch which is adapted to hold the platform in its depressed position, thereby holding the valve 85 in its closed position and preventing the escape of drip or waste water while said pan is being emptied, substantially as set forth.

6. The combination with a drip or waste 90 valve provided with a rotary plug, of a drum connected with said plug, a rocking platform which is adapted to support a drip or waste pan and which has its front end depressed by the weight of the water delivered into said pan from said valve, a cord which connects 95 the front end of the platform with said drum and whereby the valve is closed when the front end of the platform is depressed, and a spring-catch which is mounted on the front 100 end of the platform and which is adapted to engage with a stationary shoulder for holding the front end of the platform in a depressed position, substantially as set forth.

7. The combination with a drip or waste 105 valve, of a vertically-movable platform arranged below said valve, connecting means which connect the valve with the platform so that the downward movement of the platform closes the valve while the upward movement 110 of the platform opens the valve, a tray which is guided on said platform so as to be capable of moving backwardly underneath said valve or forwardly from underneath the same, and a drip or waste pan adapted to be supported by said tray underneath said valve and to be 115 withdrawn from underneath said valve by the forward movement of the tray, thereby enabling the pan to be emptied conveniently, substantially as set forth.

8. The combination with a drip or waste 120 valve, of a rocking platform arranged below said valve and connected therewith so that the valve is opened and closed by the movement of the platform, a tray supporting a drip or waste pan below the valve and having a 125 roller at its rear end which rests on the platform and rollers at its front end which are adapted to rest on the floor in front of the platform, substantially as set forth.

9. The combination with a drip or waste 130 valve, of a rocking platform arranged below said valve and connected therewith so that the valve is opened and closed by the movement of the platform, a tray supported on the

platform, and a seat or frame which is supported at intervals on the platform so as to form spaces between the seat and the platform and which is adapted to receive a drip 5 or waste pan, substantially as set forth.

10. The combination with a drip or waste valve, of a vertically-movable platform which supports a drip or waste pan below said valve and which is connected with said valve for 10 opening or closing the same, a vertically-movable indicator-plate arranged in a casting having an aperture, a spring whereby

15 said plate is moved in one direction, and a connection between said plate and the platform whereby the movement of the latter shifts said plate in the opposite direction, substantially as set forth.

Witness my hand this 10th day of August, 1900.
